UNITED STATES PATENT OFFICE.

JOHN R. MILLER, OF STERLING, ILLINOIS.

WINDMILL-REGULATOR.

SPECIFICATION forming part of Letters Patent No. 387,363, dated August 7, 1888.

Application filed December 2, 1887. Serial No. 256,750. (No model.)

To all whom it may concern:

Be it known that I, JOHN R. MILLER, a citizen of the United States, residing at Sterling, in the county of Whiteside and State of Illinois, have invented certain new and useful Improvements in Windmill - Regulators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to that class of windmill-regulators which are dependent for their action upon the height of the water in the tank into which the pump delivers.

Figure 1 is a partial section and side elevation of my apparatus; Fig. 2, a plan. Figs. 3 and 4 are detail views.

A is the usual tower or frame, upon the top of which is mounted the windmill, the latter not appearing in the drawings.

B is the pump, and B' is the pump-shaft leading up to the mill.

C is the usual chain or wire leading from the mill to the ground, the drawing of which wire downward throws the wheel out of the wind and the releasing of which allows the wheel to again turn into the wind.

C' is the bucket suspended from the end of the wire C, and it may hang above or in the well W. Said bucket is to be of proper size to hold a sufficient weight of water when filled to draw the mill out of the wind.

D is a bar having one end journaled to the tower A, as at E, and having its opposite end so connected to the bucket C' or the wire C as to move up and down with said wire and bucket.

C³ is a valve fitted to close an outlet, C², in the bottom of said bucket. To said valve is attached a cord, C⁴, which extends upward to some fixed object above, as the frame A, at such length as that, when the bucket is at its upper limit, the valve C³ will close the outlet C², and that when it is at its lower limit the valve will be raised and said outlet opened.

F' is an overflow-pipe leading from the tank F to a point above the bucket C'.

G is a bell-crank having its elbow near the side of the bar D and journaled so as to move in a vertical plane at right angles to said bar, one arm, G', of said bell-crank extending downwardly, while the other, G², extends horizontally, away from said bar D. To the end of the arm G² is coupled one end of a lever, H, the other end of which extends over the tank F. Between its ends said bar H is journaled to a fixed support, H'. From the end over the tank there is suspended a float, H². The arm G² of the bell-crank is to be made heavier than the arm G', either by making it longer or thicker or by attaching to it a weight, H³. In consequence of this preponderance of weight in the arm G², said arm will tend to descend and throw the lower end of the arm G' into the path of the bar D. When the tank F fills, the float H² rises and tilts the lever H, so as to allow the arm G² to descend and the arm G' to extend into the path of the bar D, as above stated.

The operation is as follows: The bucket C' being raised and the pump being in operation, the water rises in the tank and lifts the float H² and overflows into the bucket C'. When the latter is filled, it descends, drawing the bar D downward, the latter pushing the arm G' aside until the end thereof is passed, when said end again returns into the path of said bar D. Just after said bar D has passed by the end of the arm G', the valve C³ is drawn by the cord C⁴ and the water in the bucket is allowed to escape through the outlet C²; but the bucket cannot rise as soon as it is empty, because the end of the arm G' stands in the way of the bar D. Said bar is thus locked until the float H² descends and causes the lever H to raise the arm G² and draw the arm G' out of the path of the arm D. The latter and the bucket C' are then free to rise in response to the action of the well-known counter-balance, which holds the mill in the wind. By thus locking the bar D and bucket C' after their descent two important objects are served: First, water is prevented from freezing in the bucket; second, said bar and bucket are held down, even though the valve in said bucket may be leaky.

It is to be understood that my invention does not include apparatus in which the bucket

remains filled with water until the mill is to be thrown into action. On the contrary, my apparatus is to so operate as to drain the bucket when it reaches its lower limit and leave it

5 empty until the tank overflows again.

I claim as my invention—

1. The combination, with the windmill, of a bucket suspended from the wire or chain by which the mill may be drawn out of the wind, 10 a passage for the delivery of overflow-water into said bucket, a valve in said bucket controlled by a cord secured to a support above at proper height to cause said cord to open said valve when the bucket has descended to 15 its lower limit, an automatic locking device, substantially as described, for holding said bucket when it has reached its lowest limit, and a float for controlling said locking device, substantially as shown, and for the purposes 20 specified.

2. The combination, with a windmill, of a

wire, C, the drawing of which wire downwardly throws the wheel out of the wind, the bucket C', suspended from said wire, valve C³, located in said bucket, cord C⁴, arranged to 25 open said valve when said bucket reaches its lower limit, bar D, secured to the wire C, bell-crank G, arranged to engage said bar when the latter has reached its lower limit, lever H, connected with said bell-crank, tank F, to receive water from the pump, the float H², suspended from the lever H into the tank F, and overflow-pipe F', leading to the bucket, substantially as shown, and for the purposes specified.

In testimony whereof I affix my signature in presence of two witnesses.

JOHN R. MILLER.
